GUN SLING

Merrill K. Colby, Sparta, Mich.

Application June 23, 1950, Serial No. 169,994

2 Claims. (Cl. 224—1)

1

This invention relates to supporting devices for carrying a gun, and more particularly to a sling device adapted to be worn by a hunter and arranged for supporting a gun in a convenient position.

A main object of the invention is to provide a novel and improved gun-supporting device which is very simple in construction, which relieves the hunter of the necessity of carrying the gun in his arms and distributes the weight of the gun over his neck and shoulders, and which provides a convenient and comfortable support for the gun without interfering with its normal use in any way.

A further object of the invention is to provide an improved gun-supporting device for use by hunters, said device being inexpensive to manufacture, being provided with means to maintain the main supporting element thereof in a substantially stationary position and to prevent it from swinging away from the hunter's body at all times, and which is arranged to embracingly support the gun without causing scratching or other damage to the gun.

Further objects and advantages of the invention will become apparent from the following description and claims, and from the accompanying drawings, wherein:

Figure 1 is a view showing a hunter wearing an improved gun support according to the present invention and showing the manner in which the gun is supported in said improved support;

Figure 2 is an enlarged front elevational detail view of the main supporting element of the improved gun support of Figure 1, said view showing the end portions of the supporting strap attached to the main supporting element;

Figure 3 is a side elevational view of the structure shown in Figure 2;

Figure 4 is an enlarged fragmentary elevational view of a portion of one of the side arms of the main supporting element showing one of the articulated hooks connected thereto, as employed in the improved gun supporting device of Figures 1 to 3;

Figure 5 is an enlarged cross-sectional detail view taken on line 5—5 of Figure 2;

Figure 6 is an enlarged horizontal cross-sectional view taken through a side portion of the main supporting element of the gun-supporting device of Figures 1 to 4, showing the articulated hook attached thereto engaged with a portion of a hunter's clothing to prevent swaying of the gun support.

Referring to the drawings, 11 designates the main supporting element of the device, said main supporting element comprising a single piece of malleable tubing or the like, such as copper tubing, bent into loop form, the ends of the piece of tubing being welded, brazed or soldered together, as shown at 12. The member 11 is bent to define a pair of hook-shaped side arms 13, 13 parallel to each other and spaced apart, the top ends of said side arms being connected by a transverse, horizontal arm element 14 which includes the rigid joint 12, and the lower ends of the hook-shaped side arms 13, 13 being connected by a substantially horizontally extending, transverse arm member indicated at 15. As shown in Figure 2, the transverse arm element 15 is bowed upwardly to a slight degree, thereby defining an arcuate connecting element rather than a perfectly straight connecting element. Designated at 16 is a flexible strap of canvas or the like, said strap being of substantial width, the ends of the strap being connected, adjacent each other, to the top arm 14 of the member 11, as shown at 17 and 18. The strap 16 may be provided with any suitable means for adjusting the length thereof, such as a conventional buckle, or other suitable conventional means, such as the hooks shown at 19 in Figure 2, which are arranged to engage respective sets of eyes provided along the length of the strap 16, whereby the strap 16 may be adjusted in length in accordance with the requirements of the individual hunter.

Surrounding the lower portions of the side arms 13 and the cross member 15 is a wrapping of suitable flexible covering material, such as fabric or the like, indicated at 20, which is provided in order to protect a gun supported on the member 11 against scratches or other damage by contact with the surfaces of the cradle defined by said member 11. The wrapping 20 is preferably wound spirally, as shown in Figure 2, whereby when said wrapping becomes worn it may be readily removed and a new wrapping may be wound on the cradle member 11.

Pivotedly connected to the rear portions of the side arms 13, 13 are respective hooks, designated generally at 21, the pivotal connections of the hooks to the side arms being shown at 22. The hooks 21 may be jointed or articulated at 23, or may be completely rigid and unjointed, while still being pivotally connected to the side arms 13, 13 at 22.

In using the device, a hunter wears the strap 16 around his neck in the manner shown in Figure 1, whereby the strap bears evenly on both shoulders of the hunter. The gun is supported

in the cradle member 11, as shown in Figure 1, the cradle member 11 being located immediately below the center of gravity of the gun, whereby the gun rests in said cradle member in a substantially balanced manner. The hooks 21 are each engaged with the clothing laterally adjacent to the cradle 11, in the manner shown in Figure 6, whereby the cradle 11 is secured against lateral swaying or forward swaying, enabling the hunter to carry the gun in the support device while stooping or bending without the gun swinging away from the hunter's body.

The supporting devices may be made in different colors to match the different colors of hunting clothes, whereby the sling device may be worn inconspicuously by the hunter.

By employing malleable tubing for the cradle member 11, the weight of said cradle member is minimized, and the member may be readily formed to a proper shape to fit the individual gun of the hunter using the device.

The use of the sling device described above relieves the hunter of the necessity of carrying the gun in his arms and distributes the weight of the gun over his neck and shoulders, whereby the gun may be carried in a comfortable manner without strain on the hunter's arms. The support device does not in any way interfere with the normal use of the gun, inasmuch as the gun may be removed therefrom whenever required by merely lifting the gun out of the cradle member 11.

While a specific embodiment of an improved gun-supporting device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A gun support comprising a pair of spaced parallel main hooks, respective bar elements rigidly connecting the upper and lower ends of said hooks, said hooks being adapted to supportingly receive a gun in substantially horizontal position, a fabric cover wrapped around the lower portions of said main hooks and the lower bar element, a flexible strap connected at its respective ends to the upper bar element, said strap being adapted to be received around the neck of the

wearer, and respective smaller hooks arranged longitudinally of and in back of said main hooks adjacent and spaced from the upper ends thereof with the lower ends positioned opposite and facing away from the bottom ends of said main hooks and each pivotally connected at its upper end to the adjacent main hook for movement about an axis transverse of the latter, the lower ends of said smaller hooks being sharpened and being engageable with the clothing of the wearer to secure the main hooks against swinging.

2. A gun support comprising a closed loop member formed of tubular metal and arranged to define a pair of spaced parallel hook elements connected at their top and bottom ends by transverse bar elements, said hook elements being adapted to supportingly receive a gun in substantially horizontal position, a fabric cover wrapped spirally around the lower portions of said hook elements and the lower transverse bar element, a flexible strap connected at its respective ends to the top transverse bar element, said strap being adapted to be received around the neck of the wearer, and respective smaller hooks arranged longitudinally of and in back of said main hooks adjacent and spaced from the upper ends thereof with the lower ends positioned opposite and facing away from the bottom ends of said main hooks and each pivotally connected at its upper end to the adjacent main hook for movement about an axis transverse of the latter, the lower ends of said smaller hooks being sharpened and being engageable with the clothing of the wearer to secure the first-mentioned hook elements against swinging.
